UNITED STATES PATENT OFFICE.

JOHN R. ROSS, OF NASHVILLE, TENNESSEE.

BROOM.

SPECIFICATION forming part of Letters Patent No. 643,851, dated February 20, 1900.

Application filed July 22, 1899. Serial No. 724,796. (No model.)

To all whom it may concern:

Be it known that I, JOHN R. ROSS, a citizen of the United States, residing at Nashville, in the county of Davidson and State of Tennessee, have invented certain new and useful Improvements in Brooms; and I do declare the following to be a full, clear, and exact description of the invention, such as will enable others skilled in the art to which it appertains to make and use the same.

The invention relates to brooms.

The object is to provide a removable broom handle and head which after the broom-stock has been worn away may be easily and quickly removed from the stock and attached to a new stock.

With this object in view the invention consists in certain features of construction and combination of parts, which will be hereinafter fully described, and particularly pointed out in the appended claim.

In the accompanying drawings, Figure 1 is a perspective view of my improved broom. Fig. 2 is a longitudinal sectional view through the broom-head, broom-stock, and the clamping-bails. Fig. 3 is a detail perspective view of one of the clamping-bails.

In the drawings the same reference characters indicate the same parts of the invention.

1 denotes the broom-handle, 2 the head, and 3 the broom-stock. The head consists of a wooden block, which is secured directly to the handle, and a casing or sheave 4, made of stiff material, which is secured to the block.

5 denotes bails, the bights of which extend through the block and the ends of which are formed with transversely-arranged loops 6, which are adapted to bear firmly against the broom-stock.

7 denotes hooks, one end of each of which is secured to the transversely-disposed loops. These hooks extend through the broom-stock

below the stitching 8 and are hooked into the opposite transverse loops of the bails, the 45 spring energy of said bails being exerted in an outward direction, serving to hold the hooks in position.

When it is desired to remove the broom-stock after it becomes worn to replace it with 50 a new stock, the transverse loops of each bail are compressed and the hooked ends of the hooks disengaged from their respective loops and swung upward. Now by grasping the broom-stock and drawing it outward it may 55 be easily withdrawn from the broom-head and a new stock inserted.

From the foregoing description, taken in connection with the accompanying drawings, the construction, operation, and advantages 60 of the device will be readily apparent without requiring an extended explanation.

By the employment of a broom handle and head of my construction the cost of brooms is greatly reduced, for when the stock becomes worn and unfit for use a new stock may 65 be easily and quickly substituted therefor.

Having thus described the invention, what is claimed, and desired to be secured by Letters Patent, is—

The combination with a broom-handle, of a head composed of a block and a sheave or casing, bails having their bights extending through said block and provided at their ends with transversely-disposed loops, and hooks 75 pivoted to one of the loops of said bails and adapted to engage the opposite loops, substantially as and for the purpose set forth.

In testimony whereof I have hereunto set my hand in presence of two subscribing witnesses.

JOHN R. ROSS.

Witnesses:

EDGAR DRAKE,
JOHN DAVIS.
